UNITED STATES PATENT OFFICE

93,954

DESIGN FOR AN ASH RECEIVER

Walter von Nessen, New York, N. Y., assignor to
The Chase Companies, Incorporated, Water-
bury, Conn., a corporation

Application October 2, 1934, Serial No. 53,453

Term of patent 7 years

To all whom it may concern:

Be it known that I, WALTER VON NESSEN, a citizen of the United States, residing at New York, in the county of New York and State of New York, have invented a new, original, and ornamental Design for an Ash Receiver, of which the following is a specification, reference being had to the accompanying drawing, forming part thereof.

Fig. 1 is a perspective view of an ash receiver showing my new design; and

Fig. 2 is a similar view, viewing the ash receiver from a slightly-different angle.

I claim:

The ornamental design for an ash receiver as shown.

WALTER VON NESSEN.
